UNITED STATES PATENT OFFICE.

ELWIN K. HILL, OF VALPARAISO, INDIANA, ASSIGNOR TO SPEAR,
MARSHALL CO., OF CHICAGO, ILLINOIS, A CORPORATION OF
DELAWARE.

INHALER AND RESPIRATOR.

No. 823,946.

Specification of Letters Patent.

Patented June 19, 1906.

Application filed November 23, 1905. Serial No. 288,793.

To all whom it may concern:

Be it known that I, ELWIN K. HILL, a citizen of the United States, residing at Valparaiso, in the county of Porter and State of Indiana, have invented new and useful Improvements in Inhalers and Respirators, of which the following is a specification.

This invention relates to inhalers and respirators for the treatment of diseases of the respiratory organs; and one of the objects thereof is to provide in a manner as hereinafter set forth a device of such class with means whereby when the device is used the medicament will be heated, consequently vaporizing the same so that heated vapors, as well as heated medicated air, will be inhaled by the patient, and thereby obtaining a more satisfactory result from such treatment than would be the case if such means to heat the medicament were not employed.

The invention further aims to provide a device of the class referred to with an air-filter arranged in operative relation with respect to the pad or other means containing the medicament, so that when the device is used the air inhaled by the patient will be filtered before being medicated by its passage through the pad or other means containing the medicament.

The invention further aims to provide an inhaler and respirator with means in a manner, as hereinafter more specifically referred to, which will overcome any difficulty in breathing by the patient when using the device.

Although it is one of the objects of the invention to provide the inhaler or respirator with means in a manner, as hereinafter set forth, for vaporizing the medicament, yet the said means can be dispensed with and the device used without heating the medicament.

The invention further aims to provide an inhaler and respirator which shall be simple in its construction, provided with an electrical means for vaporizing the medicament, strong, durable, efficient in its use, easily handled, and comparatively inexpensive to manufacture.

With the foregoing and other objects in view the invention consists of the novel construction, combination, and arrangement of parts hereinafter more specifically described, and illustrated in the accompanying drawings, which form a part of this specification,

and wherein is shown the preferred embodiment of this invention; but it is to be understood that changes, variations, and modifications can be resorted to which come within the scope of the claims hereunto appended.

In the drawings, wherein like reference characters denote corresponding parts throughout the several views, Figure 1 is a perspective view of an inhaler or respirator in accordance with this invention, showing the cover removed. Fig. 2 is a vertical sectional view with the cover removed. Fig. 3 is a front view, broken away. Fig. 4 is a top plan. Figs. 5, 6, 7, 8, and 9 are details of the valve mechanism. Fig. 10 is a front view of the medicament and filter-containing receptacle. Fig. 11 is a cross-section thereof. Fig. 12 is a view showing the circuit, and Fig. 13 is a view of the pad containing the medicament. Fig. 14 is a view of the handle employed when the electrical source is formed from two or more cells.

An inhaler or respirator in accordance with this invention comprises a combined mouth and nose piece 1, preferably formed of an insulating material, although the same can be constructed of any desirable material, and when used it is adapted to be positioned over the mouth and nose of the patient. The combined mouth and nose piece is cut away at the top, as at 2, so the same will fit in a proper manner, and the edge thereof has secured thereto a suitable yielding material 3, which bears against the face of the patient when the combined mouth and nose piece is in position, so that no inconvenience will be had when the inhaler and respirator is used. Preferably the material 3 is rubber. That end of the combined mouth and nose piece which does not engage the face of the patient has formed integral therewith a perforated plate 4, said plate 4 being provided centrally with an opening 5, which is termed an "inlet-opening," for the vapor and medicated air, and surrounding the opening 5 is a concentrically-arranged series of openings 6, which are termed "outlet-openings" and which in conjunction with the inlet-opening 5 enables the patient to breathe in a satisfactory manner.

When the patient is inhaling the vapor and medicated air, the openings 6 are closed in a manner as hereinafter set forth, and when the patient is exhausting the air from his lungs the openings 6 are opened.

Fitted upon, suitably secured to, forming a continuation of, and projecting from the mouth and nose piece 1 at that end to which the plate 4 is arranged is a valve-casing 7, provided with a central opening 8, and said casing is further provided with a concentrically-arranged series of outlet-openings 9, surrounding the opening 8 and in alignment with the openings 6 in the plate 4. Supported within the opening 8 is a cup-shaped member 10, which is formed with an opening 11, termed an "inlet-opening," for the vapor and medicated air and which is in alignment with the opening 5 in the plate 4. The cup-shaped member 10 forms a seat 11^a for the inlet-valve 12, the latter being preferably formed of mica; but any other suitable material can be employed. The cup-shaped member 10 is provided at its top with a series of notches or seats 13, in which is mounted a series of radially-extending arms 14, connected together at their centers, said arms acting as a stop to limit the movement in one direction of the inlet-valve 12, and also acting as a means to constitute a seat for the outlet-valve 15, said valve 15 being preferably constructed of mica; but any suitable material may be employed, and is in the form of a flat ring and surrounds the cup-shaped member 10, as well as being positioned in advance of the outlet-openings 9. The arms 14 at the center thereof are provided with a forwardly-projecting lug 16, extending through the inlet-valve 12, and which acts as a guide for said valve, and certain of said arms 14 at the ends thereof are provided with lugs 17, which extend through the valve 15 and act as guides therefor. The movement of the valve 15 in one direction is limited by the plate 4, while the movement in the other direction is limited by the arms 14. The plate 4 upon its outer face and surrounding the inlet-opening 5 is formed with a boss 18, which when the valve-casing 7 is in position is adapted to extend in the cup-shaped member 10, so that the casing will be properly positioned, and the valve-casing 7 is formed with a forwardly-projecting annular flange 19, which is slotted, as at 20, and which constitutes one member of a coupling device for a purpose to be hereinafter referred to.

The reference character 21 denotes a receptacle for a purpose to be hereinafter referred to and which is formed with a rearwardly-extending flange 22, forming the other member of a coupling device. Said flange 22 is provided with the lugs 23, and said flange 22 in connection with the flange 19 is adapted to constitute a coupling device for connecting the receptacle 21 to the valve-casing 7, and this connection is had through the medium of the lugs 23, engaging in the slots 20 of the flange 19 and forming a pin-and-slot connection between the receptacle 21 and the valve-casing 7. The receptacle 21 at the rear end thereof is formed with an

opening 24, surrounded by the flange 22 and said rear end of the receptacle 21 is furthermore provided with a concentrically-arranged series of openings 25, which constitute air-inlet openings. Within the receptacle 21, in front of the openings 24, is arranged a filtering medium 26, and arranged within the receptacle 21, in suitable relation with respect to the opening 24, is a pad 27, adapted to contain the medicament, the position of the pad 27 being forward of the inlet-opening 11. 70 75

Carried by the flange 19 is a disk 19^a, which is positioned at such point upon said flange 19 so as to come midway between the valve-casing 7 and the receptacle 21. The function of the disk 19^a is to prevent the air that is exhaled by the patient coming into contact with the forward or removable part of the inhaler; and, furthermore, the said disk 19^a when positioned in a manner as stated causes 80 the exhaled air to pass out to the sides on the rear side of the disk and all inhaled air to be drawn through the filter from the forward side of the disk, and by such an arrangement the incoming and outgoing air are separated. 85 90

The pad 27 is provided with a resistance-wire 28, which extends through the pad from edge to edge and projects from the pad 27, and the projecting ends of said wire 28 are looped, as at 29, to permit of the mounting of the wire upon the contact-posts 30, secured to the binding-posts 31 32, which extend through the insulated end 33 of the receptacle 21, and to the said binding-posts 31 32 the leading-in wires 34 35 are connected. The leading-in wires 34 35 are connected with a suitable source of electrical energy, and a suitable switch is interposed in the circuit, so as to break and make the circuit when occasion so requires. When the circuit is made, the 100 105 resistance-wire acts to heat the pad 27, consequently vaporizing the medicament, and as the air is drawn through the inlet-openings 25 it will first pass through the filter and then through the pad. Consequently the air will not only be medicated, but will also be heated somewhat as the pad is heated owing to the action of the resistance-wire. When the circuit is broken, the pad becomes cool. Therefore it will be evident that when the 110 115 circuit is made and the device used that during the inhalation the patient will inhale the heated vapors and the heated medicated air, and which has been found to produce a more effectual result than if the vapors and air were cold.

By way of example and as showing one form for connecting the resistance-wire 28 to a source of electrical energy, and also as showing a means for making and breaking the circuit, and also for setting up the source of electrical energy with respect to the inhaler, so that the inhaler and the source of electrical energy can be very conveniently handled by the patient when using the in- 120 125 130

haler, a base 36 is provided having an upwardly-extending hollow cylinder 37, which constitutes a receptacle for a battery 38, the latter resting upon the coiled spring 39 within the cylinder 37, the function of the spring being to force the battery upwardly. The cylinder 37 has attached thereto through the medium of a pin-and slot connection 40 a metallic cap 41. As the action of the spring 39 is to force the battery 40 upwardly, the wall of the battery will be in contact at all times with the cap 41. The cap 41 centrally thereof is formed with an opening 42, through which extends one of the poles 43 of the battery, the other pole being the wall of the cell, said wall being metal and in contact with the cap 41. The cap 41 carries a contact-post 44, which is adapted to be engaged by the snap-piece 45, carried by the leading-in wire 34. The pole 43 of the battery is adapted to be engaged, in a manner as hereinafter referred to, by one end of the leading-in wire 35. That end of the leading-in wire 35 which is adapted to engage with the pole 43 is connected to a shiftable circuit making and breaking member 46, which is provided with an opening 47, into which extends the pole 43. The member 46 has projecting from each side thereof a short shaft 48, which extends through the sides 49 of a supporting-bail, the latter being connected to the cap 41, as the cap is provided centrally with an upwardly-extending boss 50, which extends through and engages the wall of the opening 51, formed in the base 52 of the bail. One of the shafts 48 carries a push-button 52', and between said button 52' and the bail is mounted a spring 53, the function of the spring 53 being to normally retain the member 46 in such position that the end of the leading-in wire 35, which is connected with said member 46, will be out of contact with the pole 43. When the member 46 is shifted by the patient engaging the push-button 52', that end of the leading-in wire 35 which is connected to the member 46 will be brought into contact with the pole 43 and make the circuit. The travel of the circuit is as follows: from the pole 43 through the leading-in wire 35, through the resistance-wire 28, thence through the wire 34, contact-post 44, cap 41 to the wall of the battery. The sides 49 of the bail are provided with eyes 54, so that a connection can be had between the valve-casing 7 and the bail, so that the latter will support the combined mouth and nose piece 1, as well as the receptacle 21. When the patient uses the device, he holds the same by grasping the cylinder 37 and utilizes his thumb to shift the member 46 to make the circuit. If desired, the cylinder 37 can be provided with a spring-clip 55 for holding a receptacle containing additional pads carrying the medicament. When the inhaler and respirator is set up in the manner as hereinbefore stated, a cover 56 is provided

and which is secured to the base 36 through the medium of the pin-and-slot connection 57.

In case it be desired to couple more than one cell as a source of electrical energy and when the patient does not desire to hold the cells a handle 58 is provided for the supporting-bail, and extending through the handle 58 are the circuit-wires 59 60, the wire 59 terminating in a contact-post 61, which is adapted to be engaged by the leading-in wire 35, carried by the shiftable member 46. When the handle 58 is employed, the wire 34 is dispensed with and the wire 59 connected directly to the post 31, said wire 59 extending through and projecting from the handle 58 in a manner as shown. The circuit is made and broken in the same manner as hereinbefore referred to.

When the device is used by a patient and during the action of inhaling, the inlet and outlet valves move in the same direction, and when exhaling they move together in a contradirection. The outlet-valve closes the outlet-openings in the plate 4 during the act of inhaling, but when exhaling the position of the outlet-valve is such that the said outlet-openings are not closed. Consequently the patient can breathe without any inconvenience. During the act of exhaling the inlet-valve closes the inlet-openings.

The pad or other means which contains the medicament is detachably mounted in the receptacle 21, so that when occasion requires the pad or other means can be moved and a new one replaced therefor. This is obvious, owing to the manner of connecting the receptacle 21 to the valve-casing and owing to the fact that the ends of the resistance-coil are looped, so that they can be conveniently mounted upon and removed off the contact posts or points 30. It will also be evident that the inhaler can be used as a protector when a person is working in a dusty or bad temperature. In this connection the combined mouth and nose piece can be used alone, the person using it fastening it to the face by a rubber band over the head. The filtering arrangement will take up the dust, and the air will enter the person's lungs clear, or if used where the air is contaminated certain disinfectants can be placed on the pad. Furthermore, the combined mouth and nose piece is adapted to be used on various machines where treatment is given by ozone and nebulized air.

Having thus fully described my invention, what I claim as new, and desire to secure by Letters Patent, is—

1. A device of the character described, comprising a combined mouth and nose piece having an inlet and an outlet, a valvular means for alternately closing and opening said inlet and outlet, a receptacle connected to said combined mouth and nose piece and

- provided with air-inlets, a filtering medium arranged in operative relation with respect to said air-inlet, a medicament-containing pad mounted in said receptacle, a resistance-wire 5 extending through said pad, electrical connections between said wire and a source of electrical energy for heating the wire, thereby vaporizing the medicament when a circuit is formed, a support for said combined 10 mouth and nose piece, and a circuit making and breaking means carried by said support.
2. An inhaler comprising a pad containing a medicament, a resistance-wire carried thereby and adapted when heated to vaporize the 15 medicament, and means for heating the wire.
3. An inhaler comprising electrical-circuit connections having as a part thereof a resistance-wire, means containing a medicament surrounding the wire, said wire when the circuit is formed, adapted to be heated, thereby 20 vaporizing the medicament, and a circuit making and breaking means interposed in said circuit connections.
4. An inhaler comprising electrical-circuit 25 connections having as a part thereof a resistance-wire, means containing a medicament surrounding the wire, said wire when the circuit is formed adapted to be heated, thereby vaporizing the medicament, a circuit making 30 and breaking means interposed in said circuit connections, and a filtering medium arranged in operative relation with respect to the means containing the medicament.
5. A device of the character described, 35 comprising a combined mouth and nose piece having an inlet and a plurality of outlets, a valve-casing connected thereto and provided with an inlet and a plurality of outlets, a valve for closing the inlet, a seat for said 40 valve, a valve for closing the outlets, a series of radially-extending arms arranged in said casing and constituting means for limiting the movement of the inlet-valve in one direction and constituting a seat for the outlet- 45 valve, said valves movable in the same direction during the act of inhalation and exhalation, a receptacle coupled to said valve-casing and provided with a series of air-inlets, means constituting the filter arranged in op- 50 erative relation with respect to said air-inlets, and means adapted to contain a medicament arranged in said receptacle.
6. A device of the character described, 55 comprising a combined mouth and nose piece having an inlet and a plurality of outlets, a valve-casing connected thereto and provided with an inlet and a plurality of outlets, a valve for closing the inlet, a seat for said valve, a valve for closing the outlets, a series 60 of radially-extending arms arranged in said casing and constituting means for limiting the movement of the inlet-valve in one direction and constituting a seat for the outlet- 65 valve, said valves movable in the same direction during the act of inhalation and exhalation, 70 a receptacle coupled to said valve-casing and provided with a series of air-inlets, means constituting the filter arranged in operative relation with respect to said air-inlets, means adapted to contain a medicament arranged in said receptacle, and supporting means for said combined mouth and nose piece.
7. A device of the character described, 75 comprising a combined mouth and nose piece having an inlet and a plurality of outlets, a valve-casing connected thereto and provided with an inlet and a plurality of outlets, a valve for closing the inlet, a seat for said valve, a valve for closing the outlets, a series 80 of radially-extending arms arranged in said casing and constituting means for limiting the movement of the inlet-valve in one direction and constituting a seat for the outlet-valve, said valves movable in the same direction 85 during the act of inhalation and exhalation, a receptacle coupled to said valve-casing and provided with a series of air-inlets, means constituting a filter arranged in operative relation with respect to said air-inlets, 90 means containing a medicament arranged in said casing and mounted in suitable relation with respect to the inlet in the valve-casing, and an electrical means for vaporizing the medicament.
8. A device of the character described, 95 comprising a combined mouth and nose piece having an inlet and a plurality of outlets, a valve-casing connected thereto and provided with an inlet and a plurality of outlets, a valve for closing the inlet, a seat for said valve, a valve for closing the outlets, a series 100 of radially-extending arms arranged in said casing and constituting means for limiting the movement of the inlet-valve in one direction and constituting a seat for the outlet-valve, said valves movable in the same direction 105 during the act of inhalation and exhalation, a receptacle coupled to said valve-casing and provided with a series of air-inlets, means constituting a filter arranged in operative relation with respect to said air-inlets, means containing a medicament arranged in said casing and mounted in suitable relation 110 with respect to the inlet in the valve-casing, a resistance-wire carried by said means containing the medicament and adapted when heated to vaporize the medicament, 115 electrical connections between said wire and a source of electrical energy, and a circuit making and breaking means interposed in said electrical connections.
9. A device of the character described, 120 comprising a combined mouth and nose piece having an inlet and a plurality of outlets, a valve-casing connected thereto and provided with an inlet and a plurality of outlets, a valve for closing the inlet, a seat for said valve, a valve for closing the outlets, a series 125 of radially-extending arms arranged in said casing and constituting means for limiting the movement of the inlet-valve in one direction and constituting a seat for the outlet- 130 valve, said valves movable in the same direction during the act of inhalation and exhalation.

- casing and constituting means for limiting the movement of the inlet-valve in one direction and constituting a seat for the outlet-valve, said valves movable in the same direction during the act of inhalation and exhalation, a receptacle coupled to said valve-casing and provided with a series of air-inlets, means constituting a filter arranged in operative relation with respect to
- 5 10 said air-inlets, means containing a medicament arranged in said casing and mounted in suitable relation with respect to the inlet in the valve-casing, a resistance-wire carried by said means containing the medicament and adapted when heated to vaporize the medicament, electrical connections between said wire and a source of electrical energy, a circuit making and breaking means interposed in said electrical connections, and supporting means for said combined mouth and nose piece.
- 15 20 25 30 35 40 45 50 55 60 65 70 75 80 85 90 95 100 105 110 115 120 125 130
10. A device of the character described, comprising a combined mouth and nose piece having an inlet and a plurality of outlets, a valve-casing connected thereto and provided with an inlet and a plurality of outlets, a valve for closing the inlet, a seat for said valve, a valve for closing the outlets, a series of radially-extending arms arranged in said casing and constituting means for limiting the movement of the inlet-valve in one direction and constituting a seat for the outlet-valve, said valves movable in the same direction during the act of inhalation and exhalation, a receptacle coupled to said valve-casing and provided with a series of air-inlets, means constituting a filter arranged in operative relation with respect to said air-inlets, means containing a medicament arranged in said casing and mounted in suitable relation with respect to the inlet in the valve-casing, a resistance-wire carried by said means containing the medicament and adapted when heated to vaporize the medicament, electrical connections between said wire and a source of electrical energy, a circuit making and breaking means interposed in said electrical connections, the source of electrical energy, supporting means for said source of electrical energy and a support for said combined mouth and nose piece interposed between the latter and the source of electrical energy.
11. An inhaler comprising a removable pad containing a medicament, a resistance-wire carried thereby and adapted when heated to vaporize the medicament, and means detachably connected with said wire for heating the same.
12. An inhaler comprising electrical circuit connections having as a part thereof a removable resistance-coil, means containing a medicament surrounding the wire, said wire when the circuit is formed adapted to be heated, thereby vaporizing the medicament, and a circuit making and breaking means interposed in the said connections.
13. An inhaler comprising a removable and replaceable means containing a medicament, circuit-forming connections detachably connected with said medicament-containing means, and a circuit making and breaking means interposed in said connections.
14. A device of the character described, comprising a combined mouth and nose piece having a centrally-disposed inlet and a concentrically-arranged series of outlets surrounding said inlet, and reciprocatory valves moving together in both directions and adapted to alternately close the inlet and outlets during the act of inhalation and exhalation.
15. An inhaler comprising a pad having a resistance-wire.
16. An inhaler comprising a combined mouth and nose piece having one end provided with an inlet surrounded by a series of outlets, a flat disk-shaped valve for opening and closing the inlet, and a flat ring arranged in operative relation with respect to said outlets and constituting an outlet-valve for opening and closing the outlets.
17. A device of the character described, comprising a combined mouth and nose piece having an inlet and an outlet and reciprocatory valves moving together in both directions and adapted to alternately close the inlet and outlet during the act of inhalation and exhalation, a receptacle connected with said mouth and nose piece and containing a medicament, and electrical means for vaporizing said medicament.
18. An inhaler comprising a combined mouth and nose piece having the forward end thereof provided with an inlet and a series of outlets surrounding the inlet, a valve-casing connected to the forward end of said combined mouth and nose piece and provided with a centrally-arranged inlet and a series of outlets surrounding said inlet, the inlet and outlets of the valve-casing position in operative relation with respect to the inlet and outlets of the combined mouth and nose piece, a valve for opening and closing said inlets, and a valve for opening and closing said outlets.
19. An inhaler comprising a combined mouth and nose piece having the forward end thereof provided with an inlet and a series of outlets surrounding the inlet, a valve-casing connected to the forward end of said combined mouth and nose piece and provided with a centrally-arranged inlet and a series of outlets surrounding said inlet, the inlet and outlets of the valve-casing position in operative relation with respect to the inlet and outlets of the combined mouth and nose piece, a valve for opening and closing said inlets, a valve for opening and closing said outlets, a

receptacle connected and communicating with said valve-casing and provided with a filtering medium and a plurality of inlets, and means interposed between the valve-casing 5 and receptacle and adapted to separate the outgoing air from the incoming air when the inhaler is used.

20. An inhaler comprising a removable pad containing a medicament, and means 10 for heating said pad.

21. A device of the class referred to, comprising a medium for carrying a medicament and a resistance-wire in circuit with a source of electrical supply for heating said 15 medium and for volatilizing said medicament.

22. An inhaler comprising a combined mouth and nose piece having an inlet and an outlet, a valve - casing suitably connected 20 thereto, a cup-shaped member mounted in said valve-casing and provided with an opening arranged in operative relation with respect to said inlet, said valve-casing provided with an outlet arranged in operative relation 25 with respect to the outlet in the combined mouth and nose piece, a valve mounted in said cup-shaped member for opening and closing said inlet, a series of supporting-arms mounted in said cup-shaped member and 30 constituting a valve-seat, and a valve carried by said arm and adapted to open and close said outlet.

23. An inhaler comprising a combined mouth and nose piece having an inlet and an outlet, a valve - casing suitably connected 35 thereto, a cup-shaped member mounted in said valve-casing and provided with an opening arranged in operative relation with respect to said inlet, said valve-casing provided 40 with an outlet arranged in operative relation with respect to the outlet in the combined

mouth and nose piece, a valve mounted in said cup-shaped member for opening and closing said inlet, a series of supporting-arms mounted in said cup-shaped member and 45 constituting a valve-seat, a valve carried by said arm and adapted to open and close said outlet, a receptacle containing a medicament and having a plurality of inlets, means for connecting the receptacle to the valve-casing 50 and a filtering medium mounted in said receptacle.

24. An inhaler comprising a combined mouth and nose piece provided with an inlet and an outlet, a valve-casing suitably connected 55 thereto, a cup-shaped member mounted in said valve-casing and provided with an opening arranged in operative relation with respect to said inlet, said valve-casing provided with an outlet arranged in operative 60 relation with respect to the outlet in the combined mouth and nose piece, a valve mounted in said cup-shaped member for opening and closing said inlet, a series of supporting-arms mounted in said cup-shaped member 65 and constituting a valve-seat, a valve carried by said arm and adapted to open and close said outlet, a receptacle containing a medicament and having a plurality of inlets, means for connecting the receptacle to the valve- 70 casing, a filtering medium mounted in said receptacle, and means for separating the outgoing air from the incoming air when the inhaler is used.

In testimony whereof I have hereunto set 75 my hand in presence of two subscribing witnesses.
